US00D925753S

(12) United States Design Patent (10) Patent No.: US D925,753 S
(45) Date of Patent: * Jul. 20, 2021

(54) HEAD MASSAGER

(71) Applicant: P.G.C.D. JAPAN, Inc., Tokyo (JP)

(72) Inventor: Taihei Noda, Tokyo (JP)

(73) Assignee: P.G.C.D. JAPAN, INC., Tokyo (JP)

() Term: 15 Years

(21) Appl. No.: 35/507,217

(22) Filed: Sep. 5, 2018

(80) Hague Agreement Data

Int. Filing Date: Sep. 5, 2018

Int. Reg. No.: DM/202198

Int. Reg. Date: Sep. 5, 2018

Int. Reg. Pub. Date: Aug. 9, 2019

(51) LOC (13) Cl. 28-03

(52) U.S. Cl.

USPC D24/214; D28/20

(58) Field of Classification Search
